United States Patent

Des. 241,738

Patented Oct. 5, 1976

241,738

TELEVISION CAMERA

Kenneth K. Lee, Los Altos, and Darrell S. Staley, Santa Clara, Calif., assignors to Ampex Corporation, Redwood City, Calif.

Filed May 21, 1975, Ser. No. 579,603

Term of patent 14 years

Int. Cl. D14—03

U.S. Cl. D16—1

FIG. 1

FIG. 2

FIG. 3

FIG. 4

FIG. 5

FIG. 1 is a top plan view of a television camera, showing our new design;

FIG. 2 is a left side elevational view;

FIG. 3 is a right side elevational view;

FIG. 4 is a front elevational view; and

FIG. 5 is a rear elevational view.

The bottom surfaces of the camera are substantially plain and unornamented.

We claim:

The ornamental design for a television camera, substantially as shown and described.
